Harry G. Gajinsky

UNITED STATES PATENT OFFICE

ALBERT E. HURST, OF NEW YORK, N. Y.

RADIATOR COVER

Application filed November 16, 1927. Serial No. 233,529.

My invention relates to a cover for the front of an automobile radiator for the purpose of providing protection during the cold weather and has for its object to provide a cover of an extremely simple form provided with means capable of being adjusted over parts of the radiator, to cover or uncover the same.

A more specific object of my invention is to provide a radiator cover of such simple form that the same may be stamped or pressed from sheet cardboard, fibre or other inexpensive material, enabling the same to be distributed gratis and providing means for effectively advertising.

Reference is to be had to the accompanying drawing, forming a part hereof in which—

Figure 1 is a front elevation of a radiator cover embodying my invention, showing the same applied on a radiator;

Figure 2 is a transverse sectional view on the line 2—2 of Figure 1, looking in the direction of the arrows;

Figure 3 is a perspective view showing my improved radiator cover as it appears before application to a radiator; and

Figure 4 is a sectional view on the line 4—4 of Figure 1, looking in the direction of the arrows.

Throughout the various views of the drawings, similar reference characters designate similar parts.

My improved radiator cover is preferably formed from a sheet of cardboard, fibre, or it may if desired, be formed from thin inexpensive metal of any kind. It is made of such form that it completely covers the front face of an automobile radiator 1 and it is provided with a peripheral edge or frame 2, the inner edge 3 of which is offset or pressed outwardly. The upper portion of the cover is cut out as at 10 to provide an open panel that exposes the upper portion 9 of the radiator. Formed integrally with or secured to the frame 2 adjacent to its lower edge is a panel 4 which is pressed out or is offset to the plane of the edging 2 or approximately so. This panel 4 as thus offset or outwardly distorted, forms a pocket to receive a vertically movable panel or sheet 5, the upper edge of which in

practice projects slightly above the upper edge of the panel 4. Means is provided for raising or lowering the panel 5, such means consisting of a flexible member or string 6 which has its lower end attached to a disk 55 or button 7 after the manner of a certain form of envelopes which have a string as a fastening means.

The upper end of the string is adapted to wrap around a second cardboard button or disk 8 which is secured upon the outer face of the edging 2.

The panel 4 is adapted to bear advertising matter as at 11 or said panel may be utilized to bear any form of ornamental design. If desired, the face of the panel 5 may also bear advertising matter, so that when said panel 5 is elevated or partly elevated, the written matter on both panels 4 and 5 can co-operate to set forth a complete message.

From the foregoing, the manner in which my improved radiator cover is used will be readily understood. In order to secure it in position on a radiator, I provide it with a plurality of fastening members 12, the same consisting of a common form of paper fastener having projecting and rearwardly extending prongs 13. These prongs are adapted to pass between the cells of the radiator as is disclosed in Figure 4, and be bent over a washer 14 which bears against the rear surface of the radiator. As many of these fastening members 12 may be utilized as may be required to securely affix the radiator cover in position.

It will be seen from the construction provided that a radiator cover is afforded which is so arranged that the exposed part of the radiator 9 may be covered or uncovered to such a degree as may be necessary. The flexible securing member or string 6 extends diagonally upward through the open panel 10 and by drawing upward on said string, the closure panel 5 may be elevated to any degree required and is readily held in such elevated position by wrapping the string around the button 8.

The construction of the radiator cover is also such that it can be readily stamped out of two pieces of cardboard and may thus be

distributed gratis since it may be used for advertising purposes and will be exceedingly successful as such, since it is a useful article which a car owner will readily apply to his car in winter weather thus affording a very prominent position for the advertisement which the cover bears.

5 I would state furthermore, that while the illustrated example constitutes a practical embodiment of my invention, I do not limit myself strictly to the exact details herein illustrated, since, manifestly, the same can be considerably varied without departing from the spirit of the invention as defined in the
10 appended claim.

15 What I claim is:

A radiator cover composed of a sheet of cardboard, said sheet having a flat marginal edge portion adapted to lie flat against the front face of the radiator, and an outwardly distorted panel about which the marginal edge portion extends, said outwardly distorted panel co-operating with the front of the radiator to form a pocket between them; an
20 open area formed in the sheet adjacent the upper part of the panel, a movable closure panel normally fitted in the pocket formed by the distorted panel and the front face of the radiator, and capable of being vertically
25 raised out of said pocket to vary the open area, means for holding said closure panel in any desired position over the open area, said means comprising a flexible securing member attached to the closure panel and passing up-
30 ward and outward through the open area, and an attaching projection to which said securing member is adapted to be connected, said projection being attached to a part of the flat marginal edge of the sheet above the
35 upper end of the open area.
40

Signed at the city, county and State of New York, this 15th day of November, 1927.

ALBERT E. HURST.
